CLAIM

The ornamental design for a tent awning, as shown and described.

DESCRIPTION

FIG. 1 is a perspective view of a tent awning according to the present design.

FIG. 2 is another perspective view of the design of FIG. 1.

FIG. 3 is yet another perspective view of the design of FIG. 1.

FIG. 4 is a front view of the design of FIG. 1; and,

FIG. 5 is a side view of the design of FIG. 1.

The claimed design comprises the elements shown in solid lines, the elements shown in dotted lines forming no part of the claimed design.

1 Claim, 3 Drawing Sheets**FIG. 1**

FIG. 2**FIG. 3**

FIG. 4

FIG. 5
